UNITED STATES PATENT OFFICE.

WILLIAM H. ROUSE AND JOHN T. FREDERICKSEN, OF DENVER, COLORADO; SAID ROUSE
ASSIGNOR TO SAID FREDERICKSEN.

EMERGENCY-BRAKE.

1,175,562.

Specification of Letters Patent. Patented Mar. 14, 1916.

Application filed June 23, 1915. Serial No. 35,762.

To all whom it may concern:

Be it known that we, WILLIAM H. ROUSE and JOHN T. FREDERICKSEN, citizens of the United States, residing in the city and county of Denver and State of Colorado, have invented certain new and useful Improvements in Emergency-Brakes; and we do declare the following to be a full, clear, and exact description of the invention, such 10 as will enable others skilled in the art to which it appertains to make and use the same, reference being had to the accompanying drawings, and to the characters of reference marked thereon, which form a 15 part of this specification.

Our invention relates to improvements in emergency brakes for vehicles our special object being to provide a brake of this character which shall be well adapted for 20 use upon motor vehicles.

The necessity for a reliable emergency brake for use on automobiles is realized by all who have had experience with machines of this character. It is well known that 25 serious accidents frequently happen on steep grades due to the fact that the regular brakes of the machine will not hold the wheels against rotation in the reverse direction, and by reason of this fact automobiles frequently become unmanageable. Our 30 improvement is intended to completely overcome this difficulty, and to this end our construction consists of a rock shaft mounted on the springs of the vehicle and carrying 35 dogs or pawls adapted to engage ratchet disks mounted on the rear wheels of the machine. The pawls are normally held out of engagement with the ratchets, by reason of a suitable connection with a crank arm 40 on the rock shaft, said connection leading to a holder or keeper which is easily accessible to the chauffeur or the person in charge of the machine. This connecting device is 45 preferably in the form of a rope or cable and its forward extremity is provided with a stop which when the cable is in engagement with the keeper, holds the rock shaft in such position that its pawls are disengaged from the said ratchets, the rock shaft 50 ever being connected with a spring which has a tendency to throw the pawls into engagement with the ratchets, and will serve to perform this function, as soon as the stop carried by the cable is disengaged from its

keeper, in which event the recoil of the 55 spring connected with the rock shaft actuates the latter and throws the pawls into engagement with the teeth of the ratchets which are carried by the wheels as aforesaid. The rock shaft is yieldingly mounted, 60 whereby provision is made to prevent the too sudden checking of the rotation of the rear wheels when the brake is applied.

Having briefly outlined our improved construction we will proceed to describe 65 the same in detail reference being made to the accompanying drawing in which is illustrated an embodiment thereof.

In this drawing,—Figure 1 is a top plan view of the rear part of a chassis of an automobile, also showing the rear wheels, 70 the springs and our improved emergency brake. Fig. 2 is a section taken through the front part of the body of the machine, showing the forward extremity of the rope 75 or cable which controls the brake. Fig. 3 is a detail view looking in the direction of arrow 3, Fig. 2. Fig. 4 is a section taken on the line 4—4, Fig. 1 viewed in the direction of the arrow, the parts being shown on a 80 larger scale. Fig. 5 is a section taken on the line 5—5, Fig. 1 looking in the direction of the arrow, the parts being shown on a larger scale. Fig. 6 is a sectional detail view, the section being taken on the 85 line 6—6, Fig. 4.

The same reference characters indicate the same parts in all the views.

Let the numeral 5 designate the rear part of the chassis or framework of an automobile, which is supported by rear springs 6. The rear wheels 7 which are fast upon the axle 8 in the usual manner, are each provided with a ratchet ring 9 which is secured by means of fastening devices 10 to 90 a circular plate 12 which is secured to the wheel by a number of U-clips 13 whose closed portions 14 pass around spokes 15 of the wheel, the threaded arms of each clip protruding through openings formed in 100 the plate 12, nuts 16 being applied thereto for securing the clips in place. This circular plate with which each wheel is equipped, forms a support for the ratchet ring 9. As shown in the drawing this ring 105 is secured to the plate by means of rivets 10. It is evident, however, that the ratchet ring may be formed integral with the plate

if desired. As illustrated in the drawing the ratchet rings 9 are located beyond or outside of the band brake drums 17.

A rock shaft 18 is journaled in spring members 19 which are secured to the upper central portions of the main springs 6 of the vehicle. The spring members 19 are relatively short and their forward portions are engaged by the U-clips 21 which connect the springs 6 with the plates 22 of the housing 23 in which the axle 8 is journaled. In order to apply the springs 19 to the main springs of the machine, it is only necessary to loosen the nuts 24 on the U-clips 21, until the closed extremities of the clips may be raised high enough to allow the spring members 19 to pass thereunder, after which the clips are secured in place and the spring members 19 are also securely held against displacement. In order to prevent the possibility of longitudinal movement of the spring members 19 in a rearward direction, the forward extremities of these springs are bent upwardly to form stops 25. The rear ends of the springs 19 or the portions extending rearwardly from the rearmost clips 21, are curved upwardly as shown at 26 above the upper surfaces of the main springs, thus leaving a considerable space 27 between the rear extremities of these springs and the upper surfaces of the main springs 6. These upturned ends of the spring members 19, are formed into eyes 28, in which the rock shaft 18 is journaled. The extremities of the rock shaft extend laterally beyond the journals 28, and their outer extremities are equipped with pawls or dogs 29, which are made fast to the rock shaft. These pawls 29 are adapted to engage the teeth 30 of the ratchet rings 9, when the rock shaft is properly adjusted.

Suitably mounted on the rock shaft are upper and lower crank arms 31 and 32. To the upper extremity of the crank arm 31 is connected as shown at 5, one extremity of a spiral spring 33 whose opposite extremity is secured as shown at 34 to the housing 23. This spring is normally under tension to actuate the rock shaft to cause the dogs or pawls 29 to engage the teeth 30 of the ratchet rings 9. In other words the tension of this spring if unresisted would move the rock shaft 18 in its bearings to cause the pawls 29 to assume the position indicated by dotted lines in Fig. 4.

Any suitable provision may be made for holding the rock shaft in position to prevent the pawls from engaging the teeth 30 of the ratchet rings 9. As shown in the drawing, the lower extremity of the crank arm 32 is connected as shown at 35, with the rear extremity of a rope or cable 36. The forward portion of this cable engages a guide pulley 37 mounted on the bottom of the body of the machine, and below or underneath, the

said pulley being mounted in a bracket 38 which is attached to the bottom 39 of the body by means of suitable fastening devices 40. Above the pulley 37, the cable 36 extends upwardly through an opening 41 formed in the bottom of the body of the machine. The cable extends upwardly above this bottom and is connected with a bracket 42 which is secured to the body of the vehicle underneath the seat as shown at 43. The bracket is provided with two spaced lugs 44 between which a cable passes. The upper extremity of the cable as shown in the drawing is equipped with a ring 45 which engages recesses 46 formed in the upper edges of the lugs, said recesses forming a sort of seat for the ring and insuring the latter against accidental displacement. The length of the cable is so regulated that when the ring 45 is seated in the recesses of the bracket lugs, the rock shaft 18 is held in such position that the pawls 29 are out of engagement with the teeth of the ratchet rings, as shown in Fig. 1 and by full lines in Fig. 4. Now in the event that it is desired to utilize our emergency brake, it is only necessary for the chauffeur or the person in charge of the machine to reach downwardly and disengage the ring 45 from its seat and allow the ring to move downwardly in response to the pull on the cable due to the recoil of the spring 33, which recoil will guide the rock shaft 18 and cause the pawls 29 to engage the teeth of the ratchet rings 9, the pawls in this event being in the position indicated by dotted lines in Fig. 4. The engagement of the teeth of the ratchets by these pawls, locks the rear wheels of the machine against rotation. At the same time the too sudden checking of the movement of the wheels is prevented by reason of the fact that the rock shaft may move downwardly in response to the stress placed upon it by reason of the engagement of the pawls with the ratchet teeth of the wheels, until the shaft supporting extremities of the springs 19 are caused to engage the upper surface of the main springs 6. It is evident that the yielding capacity of the bearing extremities of the springs 19, may be as great as desired or may have any required range. It is evident that by reason of this yielding movement of the rock shaft, there will be practically no tendency to breakage or injury to any part of the structure, due to the sudden throwing of the pawls into engagement with the wheel ratchets.

Attention is called to the fact that the rock shaft or other equivalent element of our improved construction, may be connected with other forms or arrangements of springs. For instance our improvement is equally adapted for use with vehicles having springs whose construction and arrangement are different from those shown in the

drawing. For instance the rock shaft may be connected with under-slung springs or those located below the axle, as well as with the form illustrated in the drawing. As 5 illustrated in the drawing (see Fig. 5) the two crank arms 31 and 32 are formed integral with an eye 47 which is adjustably secured to the rock shaft by means of a set bolt 48. By virtue of this specific construction, the normal position of these crank arms 10 may be regulated as desired.

Having thus described our invention, what we claim is,—

1. The combination with a vehicle, of a 15 rock shaft yieldingly mounted thereon and equipped with pawls, and means mounted on the adjacent wheels of the vehicle and coöperating with the pawls to prevent the rotary movement necessary to the rearward travel 20 of the vehicle.

2. The combination with a vehicle having a spring supported body, of a rock shaft, auxiliary spring members mounted on the main springs, and having upturned extremities in which the rock shaft is journaled, 25 pawls mounted on the said shaft, and means carried by the wheels of the vehicle and coöperating with the pawls to lock the wheels against reverse travel.

3. The combination with a vehicle having a spring supported body, of auxiliary spring members mounted on the main springs, the rear extremities of said spring members, extending upwardly above the upper surface 30 of the main springs, a rock shaft journaled in said rear extremities of said springs, pawls carried by the rock shaft, means carried by the wheels and adapted to coöper-

ate with the pawls for preventing the reverse movement of the wheels, the rock shaft being spring actuated to cause the pawls to engage the coöperating means carried by the 40 wheels.

4. The combination with a vehicle having a spring supported body, of auxiliary spring 45 members mounted on the main springs, the rear extremities of said spring members, extending upwardly above the upper surface of the main springs, a rock shaft journaled in said rear extremities of said springs, 50 pawls carried by the rock shaft, means carried by the wheels and adapted to coöperate with the pawls for preventing the reverse movement of the wheels, the rock shaft being spring actuated to cause the pawls to 55 engage the coöperating means carried by the wheels and means connected with the rock shaft and acting in opposition to its spring for holding the pawls out of engagement with the coöperating means carried by the 60 wheels.

5. The combination with a vehicle of a rock shaft yieldingly mounted thereon, means mounted upon adjacent wheels of the vehicle, and means carried by the rock shaft 65 adapted to engage the first named means to prevent the rotary movement necessary to the rearward travel of the vehicle.

In testimony whereof we affix our signatures in presence of two witnesses.

WILLIAM H. ROUSE.
JOHN T. FREDERICKSEN.
